CLAIM

The ornamental design for a cosmetic tool with rolling applicator, as shown and described.

DESCRIPTION

FIG. 1 is a right side elevational view of a cosmetic tool with rolling applicator showing an additional embodiment of the new design;

FIG. 2 is a left side elevational view of the embodiment illustrated in FIG. 1;

FIG. 3 is a front elevational view of the embodiment illustrated in FIG. 1;

FIG. 4 is a rear elevational view of the embodiment illustrated in FIG. 1; and,

FIG. 5 is top plan view of the embodiment illustrated in FIG. 1.

Surface shading is used to shade FIGS. 1-5 to show clearly the character and contour of all surfaces of the 3-dimensional aspects of the design and form a part of the design sought to be protected. The broken lines are for illustrative purposes only and form no part of the claimed design.
